UNITED STATES PATENT OFFICE.

MICHAEL NEIL AND FRANK H. BISSELL, OF DAYTON, OHIO.

WIRE FENCE.

SPECIFICATION forming part of Letters Patent No. 602,867, dated April 26, 1898.

Application filed July 29, 1897. Serial No. 646,313. (No model.)

To all whom it may concern:

Be it known that we, MICHAEL NEIL and FRANK H. BISSELL, citizens of the United States, residing at Dayton, in the county of 5 Montgomery and State of Ohio, have invented certain new and useful Improvements in Wire Fences, of which the following is a specification.

Our invention has relation to stays for the 10 runners of wire fences; and in such connection it relates to the particular construction and arrangement of the stays in conjunction with the runners of a fence to permit pressure being exerted against the runners without 15 causing permanent derangement of the same and to afford certain substantially universal movements of the runners without actual permanent displacement or disfigurement thereby of the fence.

20 The principal object of our invention is to provide a simple, inexpensive, and effective and substantially universal telescoping stay for a wire fence in which particularly the runner embraced thereby is afforded a certain 25 defined range of vertical movement as well as lateral and other movements without disarranging or disorganizing the fence in its entirety and at the same time providing a stay which is substantial, readily applied to 30 or coupled with the runners, and at the same time more or less ornamental in appearance.

Our invention consists of the improvements in stays for wire fences when constructed and arranged in the manner hereinafter described 35 and claimed.

The nature and scope or characteristic features of our invention will be more fully understood from the following description, taken in connection with the accompanying drawings, forming part hereof, in which—

Figure 1 is a side elevational view of a wire fence with a stay embodying the main features of our invention shown in application to the line wires or runners of the fence. Fig. 45 2 is a similar view, on an enlarged scale, of the stay of our said invention in application to the line wires or runners of the fence; and Fig. 3 is an end view of the same.

Referring to the drawings, A and A' represent 50 two vertical posts of a fence of any suitable construction and which are engaged by

a series of longitudinal line wires or runners B.

C is the stay of our present invention, consisting of the loop-shaped members c and c', 55 linked together in series. Each member is formed into a double oblong or, preferably, oppositely-tapering double connected loop, the terminals of which united or connected loops are twisted, preferably, in opposite directions upon the bar c² of the member in the form of a coil c³ at or about the middle of the same, as clearly and fully illustrated in Figs. 2 and 3. The connected complementary members at the point of linked connection are 65 adapted, when a line wire or runner of the fence is inserted through the same, to form a more or less circular bearing c⁴ for such line wire or runner. This bearing c⁴ is adapted to permit of the telescoping of the same and 70 of a more or less universal movement of one member of the connected stay with respect to the other when pressure is exerted upon or against the line wire or runner B of the fence, as will be readily understood from Fig. 2 of 75 the drawings; and also a certain range of vertical movement in the bearings c⁴ of the connected stay C, whereby when the energy which influenced any of said movements is relieved or removed the respective line wires 80 or runners will return to initial positions in the bearings c⁴ of the stay C—for example, the position illustrated in Figs. 1 and 2 of the drawings. The stays C, as to the topmost and bottommost members thereof, are secured 85 to the top and bottom line wires or runners B by being preferably coiled around the same—for instance, as shown in the drawings.

Among the advantageous features of our invention may be mentioned that the said 90 jointed stay effectually and reliably permits of a universal movement of the wires of the fence without derangement or displacement of the same, which is due to the character, length, and arrangement of the loop, affording 95 thereby the telescoping feature thereof as well as an easy yielding of the same in different directions from any given point, thereby rendering the defined stay especially desirable in fence construction and particularly 100 so because of the ability to maintain the line wires or runners in connection therewith in

their relative symmetrical locations or positions in the fence.

Having thus described the nature and objects of our invention, what we claim as new, and desire to secure by Letters Patent, is—

In a wire fence, in combination with longitudinal wires or runners, of a stay consisting of a series of linked members, of which each of the terminal members consists of a single strand having one end coiled around the upper or lower runner and the other end coiled about the body of the strand to form a loop, the complementary or intermediate links of the stay each consisting of a double-looped strand, the ends of the strand being coiled in opposite directions upon the body of the link,

the links of the stays being coupled or looped together to form a substantially universal joint c^4 , adapted to receive and retain an intermediate runner and to support the same in position and permitting of a vertical movement of said runner, substantially as shown and described.

In testimony whereof we have hereunto set our signatures in the presence of two subscribing witnesses.

MICHAEL NEIL.
FRANK H. BISSELL.
